UNITED STATES PATENT OFFICE.

JOHN B. BARTHOLOMEW, OF PEORIA, ILLINOIS, ASSIGNEE TO THE BARTHOLOMEW COMPANY, A CORPORATION OF ILLINOIS.

LUBRICATOR.

1,116,784.

Specification of Letters Patent. Patented Nov. 10, 1914.

Application filed July 27, 1908. Serial No. 445,592.

To all whom it may concern:

Be it known that I, JOHN B. BARTHOLOMEW, a citizen of the United States, residing at Peoria, in the county of Peoria and State of Illinois, have invented certain new and useful Improvements in Lubricators, of which the following is a specification, reference being had therein to the accompanying drawing.

This invention relates to the improved system of lubrication for engines, of the type shown in my application for patent Serial Number 320,798, filed June 8, 1906. As remarked in the aforesaid application, the system, while it may be said, in general, to be of the splash type, possesses certain added features not heretofore employed in lubricating devices of the splash type, the object of said features being to obtain more perfect lubrication under certain conditions of operation, especially the conditions met with in the motor vehicle art.

The present invention relates more particularly to structural matters, having for its object the production of a simple, compact and generally efficient structure.

The nature of the invention will be clearly understood from the following description, in connection with the drawings, in which I have shown the invention applied to a multiple cylinder internal combustion engine of the sort employed to drive motor vehicles.

In the drawings, Figure 1 is a vertical, longitudinal section of a four-cylinder engine embodying my improvements, the section being taken on the line $x-x$ of Fig. 4, and some of the parts being shown in elevation. Fig. 2 is a sectional elevation of the right end of said engine, the section being taken on the line $y-y$ of Fig. 4. Fig. 3 is a transverse vertical section, taken on the line $z-z$ of Fig. 1. Fig. 4 is a plan view of one end of the engine.

Referring in detail to the construction illustrated, 1-1 are the cylinders mounted in the well known manner on the upper part 2 of the crank case. The lower part 3 of the crank case embodies many of the novel features of my invention presently to be described.

The crank shaft 4 is supported in bearings 5-5 at each end of the crank case, and intermediate bearings 6-6 carried by depending arms 7-7. The construction of

these bearings and of the crank shaft 4, connecting rods 8-8 and pistons 9-9 as well, need not be described in detail for they are shown in old and well known forms.

The lower or pan part 3 of the crank case is formed in casting with a double bottom 10-11 with an intervening chamber or compartment 12. The crank chamber communicates with compartment 12 through a series of overflow ducts or ports 13, which are disposed at the level at which it is desired to maintain the oil in the bottom of the crank chamber. The bottom part of the crank chamber is divided into a number of compartments, preferably one for each of the cranks, by means of transverse ribs 14. Thus the oil is prevented from flowing freely from end to end of the crank case, when it is tipped, as, for example, when the vehicle is going up or down a grade.

At one end the lower part 3 of the crank case is provided with an extension 15 designed to inclose a pump 16 and the devices for operating the said pump. The pump 16, as shown, is of the rotary gear type having an upstanding driving shaft or spindle 17 to which is loosely or detachably coupled a depending shaft 18 which carries a gear 19 meshing with and driven by a companion gear 20, on the crank shaft 4. The shaft 18 is supported in a bearing 21 carried by the crank case. The upper part 2 of the crank case is formed with an extension 22 which in connection with the extension 15 of the lower part of the case incloses the gearing 19-20. The bottom or floor of the chamber, formed by the extension 15, is preferably upon the same level, or is at least as low as the lowest part of the floor of the chamber or compartment 12, and the pump 16 is mounted with its suction or supply passage 23 close to the bottom or floor of the extension 15, so as to insure a supply of oil to the pump at all times. The tube 24 leads from the discharge passage of the pump upward into the crank chamber, and extends horizontally adjacent the wall of the chamber, as is clearly shown in Figs. 1 and 3. The horizontal part of the tube is provided with discharge ports 24', of which there are one or more for each of the compartments formed by the transverse ribs 14.

I prefer to provide means for indicating the oil level and employ for this purpose a glass tube 25, which is connected by means

of suitable fittings 26 with the lower part of the chamber extension 15, as is clearly shown in Fig. 2. The sight tube is provided with a cap or closure 27 which may be removed when it is desired to replenish the supply of lubricant in the oil compartment.

I shall now describe the operation of the mechanism, pointing out incidentally, the advantages which it possesses, particularly in connection with engines which must operate under the conditions met with in motor vehicle practice.

The crank case being filled with oil up to the overflow passages 13, and the receptacle or compartment 12 being also filled with oil, the operation of the pump serves to lift the oil from compartment 12, forces it through the tube 24 and through the discharge apertures of the latter into the crank case. It will be understood that the oil may flow gently through the apertures, or may be discharged in the form of jets, according to the speed of the pump, which, of course, will be determined by the ratio of the gears which drive the pump. In either case the oil is distributed throughout the length of the crank case and finds its way into the several compartments formed by the transverse ribs or webs 14. The surplus oil is drawn off from the several compartments through the overflow passages 13, into the compartment 12, as rapidly as it accumulates, and thus the oil is maintained at the desired level in the said compartments. Into the several bodies of oil thus maintained, the cranks and connecting rods dip as the shaft turns splashing and churning the oil in the well known manner so as to lubricate the piston, cylinder and bearing connections between the pistons and connecting rods, as well as all of the crank shaft bearings. If the engine be considerably inclined by tipping about a transverse axis, as in passing up or down hill, it is clear that the transverse webs will prevent the oil from running freely to the lower end of the crank case, so as to deluge the lowermost crank pins, while leaving those at the upper end of the crank case practically dry, the injurious effects of leaving the bearing parts of one or more of the cylinders dry is obvious, and it is also well understood by those familiar with this art that a surplus of lubricant results in the fouling of the cylinders and ignition devices.

It is clear that the engine constructed, as above described, although possessing the desirable features of lubrication of the en-

gine shown and described in my prior application above referred to, is entirely self-contained and is scarcely greater in bulk than the ordinary engine having a plain crank case. The number of parts also is reduced to a minimum.

Having thus described my invention, what I claim is:

1. In a lubricator for an internal combustion engine, the combination of a crank case having formed within it and inclosed by the outer walls thereof a main oil reservoir, a crank chamber above the reservoir and adapted for holding a limited amount of oil, a duct for leading the overflow of oil from the crank chamber back to the reservoir, and a pump within the crank case, the walls of the crank case on all sides of the pump extending to points above the level of the oil in the reservoir.

2. In a lubricator for an internal combustion engine, the combination with a crank case having formed within it and inclosed by the outer walls thereof a main oil reservoir, a crank chamber above the reservoir and adapted for holding a limited amount of oil, a duct for leading the overflow of oil from the crank chamber back to the reservoir, of a pump within the crank case, the walls of the crank case extending upward to points above the oil level in the reservoir, and a pump driving mechanism arranged on lines within the crank case and extending from the pump to points above the oil level in the reservoir, whereby leakage of oil to points exterior to the crank case is prevented.

3. In a lubricator for internal combustion engines, the combination of a crank case having formed within it and inclosed by the outer walls thereof a main oil reservoir, a crank chamber above the reservoir and adapted for holding a limited amount of oil, a duct for leading the overflow of oil in the crank chamber back to the reservoir, a pump within the crank case, the walls of the crank case on all sides of the pump extending to points above the oil level in the reservoir, and the pump driving mechanism positioned to extend upward through an opening in the crank case located above the oil level in the reservoir.

In testimony whereof I affix my signature, in presence of two witnesses:

JOHN B. BARTHOLOMEW.
